FOUNDATION GARMENT

George L. Diebold, Chicago, Ill., assignor to Venus Foundation Garments, Inc., Chicago, Ill., a corporation of Delaware

Application May 20, 1952, Serial No. 288,923

14 Claims. (Cl. 2-37)

1

This invention relates to improvements in foundation garments and more particularly to a novel and improved girdle construction.

For satisfactory performance a girdle should provide the wearer with an attractive rear contour when standing, i. e. the desired flattening of the buttocks in both horizontal and vertical planes or cross-sections. In addition, the garment must also be comfortable when the wearer is sitting or bending. Numerous girdle constructions have been proposed utilizing various combinations of rigid and elastic materials for the back portion or rear of the garment to approximate these objectives, but in most instances the garment has failed to provide the desired performance during use in one or several important respects.

The provision of a single rear panel of rigid or non-elastic material is unsatisfactory principally because of lack of comfort during bending or sitting. A single one-way horizontal stretch panel permits greater comfort for the wearer but fails to provide adequate flattening or contour control in horizontal cross-section because of the uncontrolled horizontal stretchability of the panel. A single panel at the rear of one-way vertical stretch material is likewise inadequate because it fails to provide the required flattening effect in vertical cross-section. In addition, in the case of a single rear panel of rigid material or one-way vertical stretch material, the substantial width and horizontal non-elasticity of the panel limits the flattening effect thereof and there is also a definite tendency for the wide panel to belly or bulge under certain circumstances. The use of a single panel of two-way stretch material at the rear of the garment does not solve the difficulty because it merely introduces a combination of the foregoing defects.

Accordingly, it is a primary object of my invention to provide a novel rear panel construction for foundation garments which overcomes the defects and objections heretofore noted in articles of this character.

A further object of the invention is to provide a novel rear panel construction for foundation garments, such as girdles and the like, which provides the wearer with the desired attractive rear contour when standing and is also comfortable when the wearer is sitting or bending.

Another object of the invention is to provide an improved multi-panel construction for the rear portions of foundation garments which affords greater and more selective contour control than heretofore available in such garments.

2

Other objects and advantages of the invention will become apparent from the subsequent detailed description taken in conjunction with the accompanying drawing, wherein:

5 Fig. 1 is a front elevational view of a girdle embodying the principles of my invention;

Fig. 2 is a rear elevational view of the girdle seen in Fig. 1;

Fig. 3 is a plan view of the interior of the garment as the latter would look if broken and spread out;

Fig. 4 is a front elevational view of a girdle embodying a modified form of the invention;

Fig. 5 is a rear elevational view of the girdle shown in Fig. 4; and

Fig. 6 is a plan view of the interior of the garment shown in Figs. 4 and 5 as the latter would look if broken and spread out.

Although the invention is hereinafter described in connection with a girdle, it will be understood that the principles involved are equally applicable to other types of garments such as panty girdles and all-in-one combination garments having a bust or brassière top.

20 Referring first to Figs. 1 to 3, my invention resides primarily in a novel back portion for the girdle including a main panel of horizontally stretchable material and a pair of relatively narrow elongated control panels secured to the main panel and disposed in transversely spaced relation. The material of the control panels may be the same as the main panel or it may have substantially greater resistance to horizontal stretching or elongation than the main panel. The control panels are so located as to overlie the buttocks of the wearer during use. As will be seen hereinafter, the effect of the control panels is to provide spaced areas or regions at the rear of the garment which have a lesser degree of horizontal stretchability or extensibility than the main panel for obtaining the desired contour control and flattening action in horizontal cross-section while at the same time the main panel permits the required expansion for providing comfort during bending and sitting.

25 In Fig. 1 a front view of the garment is shown for the sake of completeness although the particular construction of the front portion of the garment does not form any part of the present invention. In the embodiment illustrated in Figs. 1 to 3, the front portion of the girdle comprises two-part main elastic panel 11, preferably having both horizontal and vertical stretchability or extensibility, and a front insert 12 fitted between the two parts of the main panel 11 and adapted

to overlie the abdomen of the wearer. The insert 12 is secured by suitable stitching 13 to the two parts of the main panel 11. The insert 12 is preferably of one-way vertical stretch material to provide the desired horizontal flattening effect over the abdomen. The usual stiffening elements 14 are provided adjacent the top edge of the front portion of the garment. The front portion is connected to the back portion of the garment by suitable side seams 15 and 16 with the customary zipper or like closure means being provided, as at 17.

The rear portion of the garment which comprises the principal feature of the present invention is illustrated in Figs. 2 and 3. In this embodiment, the back portion includes a main panel 18 extending across substantially the entire width of the garment and being formed of a material having substantial horizontal stretchability or extensibility. In the preferred form of the invention, the main panel 18 is extensible both horizontally and vertically. For example, the two-way stretch material known to the trade as a Leno weave fabric having elastic or rubber yarns both in the filling and the warp may be employed. However, it is also within the scope of my invention to employ a material having extensibility in both horizontal and vertical directions but having a true elastic stretchability in only one direction. For example, a Leno weave fabric having elastic or rubber warp yarns and rigid filling yarns of rayon or the like will provide the desired action since this fabric can be used to form a main panel 18 which is truly elastic in a horizontal direction but is capable of elongation or extensibility by distortion in a vertical direction. Another material having these desired characteristics is known in the trade as elastic net. Thus, it is to be understood that when I refer to a material having both horizontal and vertical stretchability or extensibility, it is intended to include not only the conventional two-way stretch elastic fabrics but also the materials which give substantially the same results even though not strictly known as two-way elastic stretch materials.

For ease of fabrication, the main rear panel 18 may be formed with a central longitudinal seam 19 if desired. In addition, the usual rear stiffening elements 20 extend downwardly adjacent the upper edge of the back portion of the garment.

The novel aspect of my invention resides in a pair of relatively narrow vertical elongated control panels 21 which, in the present embodiment, are shown as superimposed over the main panel 18 at the inside thereof and appliqued thereto by means of peripheral stitching. The control panels 21 are disposed in transversely spaced relation on the main panel 18 so as to overlie the buttocks of the wearer during use. The control panels 21 in this instance are formed from a material having a lesser degree of horizontal stretchability or extensibility than the main panel 18. In the preferred form of the invention, as clearly illustrated by the direction of the threads in Fig. 3 the control panels 21 are formed from a material having one-way vertical stretchability or extensibility and being substantially rigid or non-stretchable in a horizontal direction. As a result, it will be understood that the resistance of the control panels 21 to horizontal stretching drastically limits the horizontal stretchability of that portion of the underlying main panel 18 to which the control panels are attached and thereby provides the desired degree of contour control and flattening action on the buttocks in hori-

zontal cross-section. The transversely spaced relation of the control panels 21 not only serves to position the panels over the respective buttocks but also permits the horizontally stretchable material comprising the main panel 18 to act on each of the opposite vertical sides of the control panels whereby to provide horizontal tension at each side of the control panels.

Although in the above-described embodiment the material of the control panels 21 has a lesser degree of horizontal stretchability or extensibility than the material of the main panel 18, it is also within the scope of my invention to utilize the same material for the panels 21 as in the panel 18. In such case the superimposed relation of the control panels 21 over the main panel 18 produces a double thickness of material so that the regions or areas of the garment covered by or within the confines of the control panels 21 have a greater resistance to horizontal stretching or extension than the main panel 18. Thus, the result obtained by the effect of the double thickness of material is equivalent to the result obtained when the material of the panels 21 has lesser horizontal stretchability or extensibility than the panel 18.

Another feature of the invention resides in the peripheral contour or configuration of the control panels 21. As will be evident from the drawing, the panels 21 have generally curved side edges tapering toward the opposite ends of the panels so that the panels 21 are widest at their intermediate or central portions. In Fig. 2, a broken line 22 has been drawn to locate in schematic fashion the buttocks of the wearer during use of the garment, and it will be evident that the widest portions of the control panels 21 are disposed over the fattest regions of the buttocks thereby exerting the maximum flattening action in these regions where it is most needed.

By the foregoing combination of a horizontally stretchable or extensible main panel and the pair of control panels imparting a lesser degree of horizontal extensibility, I am able to accomplish both of the aforementioned objectives of a girdle construction, namely, the provision of adequate contour control when standing and substantial comfort during sitting or bending, in a novel and highly successful manner.

Referring now to Figs. 4-6, there is shown a slightly different embodiment of the invention involving the same principle of using a pair of transversely spaced control panels to limit the horizontal stretchability or extensibility of the main rear panel over the fatty regions of the buttocks. Fig. 4 shows the front of the garment for completeness, but again the front construction forms no part of the present invention. In this instance the front of the girdle has a two-part main elastic body 23 with a somewhat differently shaped restraining insert 24 adapted to overlie the abdomen as before. A side stiffening element 25 is provided at one side of the garment adjacent a side seam 26 and a zipper closure 27 is provided at the other side with a seam 28 therebelow. Additional stiffeners 29 (Fig. 6) extend downwardly from the upper edge of the girdle at the front thereof.

In this embodiment, the rear portion of the girdle (Fig. 5) has a multiple piece or interrupted construction including a pair of side portions 30 which are connected to the front portion 23 by the seams 26 and 28. Instead of the superimposed or appliqued relation of the control panels to the garment body as described in connection with Figs. 1 to 3, the present embodiment pro-

vides a pair of control panels in the form of inserts 31 which are bodily interposed between the side portions 30 and a central piece 32 which is of the same material as the side portions 30. The control panels or inserts 31 are connected by edge stitching 33 to the corresponding edges of the portions 30 and 32 and are disposed in transversely spaced relation as before. The panels 31, although of somewhat modified configuration as compared to the panels 21, are also widest at their central portions and are tapered slightly from their central portions to their ends for the same reasons discussed above. As in the first described form of the invention, the material forming the control panels 31 has lesser horizontal stretchability or extensibility than the material forming the portions 30 and 32 so that the desired contour control is obtained over the buttocks region. Preferably, the portions 30, 32 have two-way extensibility and the inserts 31 are extensible vertically but substantially non-extensible horizontally. A pair of stiffeners 34 also extend down from the upper edge of the garment at the rear thereof.

Although the invention has been described in connection with certain specific embodiments thereof, it will be understood that various modifications and alternative constructions may be resorted to without departing from the scope of the invention as defined in the appended claims.

I claim:

1. In a garment of the character described having connected front and back portions, a back portion comprising a main panel of horizontally stretchable material and a pair of elongated control panels having their longitudinal dimensions extending vertically relative to said main panel and disposed in transversely spaced relation with part of said main panel secured therebetween to the side edges of said control panels, said control panels having greater resistance to horizontal stretching than said main panel and being spaced a predetermined distance whereby to overlie the respective buttock areas of the wearer during use.

2. In a garment of the character described having connected front and back portions, a back portion comprising a horizontally and vertically stretchable main panel extending substantially the entire width of the garment, and a pair of elongated control panels having their longitudinal dimensions extending vertically relative to said main panel and having substantially greater resistance to horizontal stretching but having substantially no greater resistance to vertical stretching than said main panel, said control panels being transversely spaced from each other and from the sides of said main panel a predetermined distance whereby to overlie the respective buttock areas of the wearer during use and said control panels being secured along their side edges to said main panel.

3. In a garment of the character described having connected front and back portions, a back portion comprising a pair of elongated vertically extending control panels transversely spaced a predetermined distance whereby to overlie the respective buttock areas of the wearer during use, and a main panel of horizontally and vertically elastic material extending between said control panels and adjacent the outer edges thereof, said control panels being secured along their side edges to said main panel and extending vertically relative to said main panel, and said control panels having substantially greater re-

sistance to horizontal stretching but having substantially no greater resistance to vertical stretching than said main panel whereby to facilitate contour control and flattening in horizontal cross-section substantially entirely by the increased resistance to horizontal stretching in said areas.

4. In a garment of the character described having connected front and back portions, a back portion comprising a pair of elongated control panels having substantially no horizontal stretchability and transversely spaced a predetermined distance whereby to overlie the respective buttock areas of the wearer during use, and a main panel of horizontally stretchable elastic material having a center portion between said control panels and side portions at the outer sides of said control panels, said control panels extending vertically relative to said main panel and being secured along their respective side edges to said center portion and said side portions of said main panel whereby to provide horizontal tension at each side of said control panels for exerting substantial flattening and contour control over the buttocks region in horizontal cross-section.

5. In a garment of the character described having connected front and back portions, a back portion comprising a main panel of elastic material extensible both horizontally and vertically, and a pair of transversely spaced control panels extending vertically relative to said main panel and made of one-way vertically stretchable material having substantially no horizontal stretchability, said control panels being secured along their side edges to said main panel with part of the main panel therebetween, and said control panels being spaced a predetermined distance whereby to overlie the respective buttock areas of the wearer during use.

6. In a garment of the character described having connected front and back portions, a back portion comprising a main panel of horizontally stretchable material, and a pair of vertical elongated control panels having their longitudinal dimensions extending vertically relative to said main panel superimposed over said main panel and connected thereto in transversely spaced relation with part of said main panel therebetween, said control panels having substantially greater resistance to horizontal stretching than said main panel and being spaced a predetermined distance whereby to overlie the respective buttock areas of the wearer during use.

7. In a garment of the character described having connected front and back portions, a back portion comprising a main panel of elastic material extensible both horizontally and vertically, and a pair of vertical elongated control panels of one-way vertically stretchable material having substantially no horizontal stretchability superimposed over said main panel in transversely spaced relation and connected to said main panel with part of said main panel therebetween and with the longitudinal dimensions of said control panels extending vertically relative to said main panel, said control panels being spaced a predetermined distance whereby to overlie the respective buttock areas of the wearer during use for exerting a controlled flattening effect thereon.

8. In a garment of the character described having connected front and back portions, a back portion comprising a main panel of elastic material stretchable horizontally and a pair of transversely spaced elongated vertical control panels connected at their opposite sides to said main panel with part of said main panel there-

between and with the longitudinal dimensions of said control panels extending vertically relative to said main panel, said control panels being spaced a predetermined distance whereby to overlie the respective buttock areas of the wearer during use, and said control panels having greater resistance to horizontal stretching than said main panel and being widest at their central portions intermediate their upper and lower end portions whereby to provide the greatest flattening effect and contour control at the fattest portions of the buttocks.

9. In a garment of the character described having connected front and back portions, a back portion comprising a pair of spaced vertical control panels adapted to overlie the buttocks of the wearer during use and a main panel of elastic horizontally stretchable material extending between and adjacent the outer side edges of said control panels with said control panels extending vertically relative to said main panel and being connected along their side edges to said main panel, said control panels having substantially greater resistance to horizontal stretching than said main panel and having generally curved side edges tapering toward the opposite ends thereof whereby the widest portions of said control panels are adapted to be disposed over the fattest regions of the buttocks for exerting the greatest flattening effect at said regions.

10. In a garment of the character described having connected front and back portions, a back portion comprising a pair of vertical control panels spaced transversely a predetermined distance whereby to overlie the respective buttock areas of the wearer during use and having substantial resistance to horizontal stretching, and elastic horizontally stretchable panel means having said control panels connected thereto along the respective side edges of said control panels between the latter and at the outer sides thereof for exerting buttocks-flattening tension on said control panels, said control panels extending vertically relative to said panel means and the width of said control panels being greatest at their central portions intermediate their upper and lower end portions for exerting maximum flattening action at the fattest portions of the buttocks.

11. In a garment of the character described having connected front and back portions, a back portion comprising a main panel of horizontally and vertically extensible material, and a pair of elongated vertical control panels of one-way vertically stretchable material superimposed in transversely spaced relation on said main panel and connected thereto adjacent the edges of said control panels with part of the main panel between said control panels, said control panels

having their longitudinal dimensions extending vertically relative to said main panel and being spaced a predetermined distance whereby to overlie the respective buttock areas of the wearer during use and having relatively wide central portions with tapered upper and lower end portions whereby the widest portions of the control panels are adapted to be disposed over the fattest regions of the buttocks for exerting the greatest flattening effect at said regions.

12. In a garment of the character described having connected front and back portions, a back portion comprising a main panel of material having substantial horizontal extensibility, and a pair of control panels comprising elongated inserts bodily interposed in said main panel in transversely spaced relation and having their longitudinal dimensions extending vertically relative to said main panel whereby portions of said main panel are disposed at the outer edges of said inserts and also between the latter, said inserts being secured along their side edges to the respective edges of said main panel and being of material having substantially greater resistance to horizontal extension than said main panel and being spaced a predetermined distance whereby to overlie the respective buttock areas of the wearer during use.

13. The article of claim 12 further characterized in that the material of said main panel is extensible both horizontally and vertically and the material of said inserts is extensible vertically but substantially non-extensible horizontally.

14. In a garment of the character described, a front and a back, the back having a substantially vertical central strip portion which is horizontally extensible and also having substantially vertical control strip portions on each side of said central strip portion of substantially greater resistance to horizontal extension than said central portion, said control strip portions extending vertically relative to the back of the garment and being secured along their side edges to said central strip portion and being spaced transversely a predetermined distance whereby to overlie the respective buttock areas of the wearer during use.

GEORGE L. DIEBOLD.
